DICE SET

Alfred H. Keast, San Francisco, Calif.

Application January 26, 1948, Serial No. 144,015

Term of patent 7 years

(Cl. D34—5)

To all whom it may concern:

Be it known that I, Alfred H. Keast, a citizen of the United States, residing at San Francisco, State of California, have invented a new, original, and ornamental Design for Dice Set, of which the following is a specification, reference being had to the accompanying drawing, forming a part thereof.

Fig. 1 is a view of the first face of each die in the set of dice, showing my new design;

Figs. 2, 3, 4, 5 and 6, respectively, show the second, third, fourth, fifth, and sixth faces of each die in the set of dice, the six faces of each die being shown in the same horizontal row.

The total number of dice in the set is 8.

The figures are shaded to show color contrast.

I claim:

The ornamental design for a dice set, as shown and described.

ALFRED H. KEAST.
